UNITED STATES PATENT OFFICE.

ALEXANDER T. YOUNG, OF EAST CHINA, ST. CLAIR COUNTY, MICHIGAN.

STOVE.

SPECIFICATION forming part of Letters Patent No. 323,250, dated July 28, 1885.

Application filed June 4, 1884. (No model.)

To all whom it may concern:

Be it known that I, ALEXANDER T. YOUNG, of East China township, in the county of St. Clair and State of Michigan, have invented certain new and useful Improvements in Stoves, of which the following is a full, clear, and exact description.

The object of my invention is to provide certain new and useful improvements in stoves, whereby the quantity of coals to be consumed by the fire may be regulated, and the heat may be increased or diminished at will; also, different kinds and sizes of coal may be used in the same stove, all of which can be accomplished very easily.

The invention consists in the combination, with the magazine of a stove, of a ring held to move vertically in the magazine, a screw for moving the ring vertically, and of downwardly-projecting prongs forming a basket for holding the coals, which basket is opened by raising the ring and prongs and closed by lowering them, and may be done by inclosing the lower end of prongs in a movable notched ring having a hub screwed onto the lower end of vertical screw, which ring when raised by said screw will close said basket, and when lowered, open it, the basket remaining stationary in the magazine; or the basket may be raised and lowered by a rotary shaft and chains.

Reference is to be had to the accompanying drawings, forming part of this specification, in which similar letters of reference indicate corresponding parts in all the figures.

Figure 1 is a cross sectional elevation of my improved attachment for stoves. Fig. 2 is a plan view of the same. Fig. 3 is a cross-sectional elevation of a modified form of my improvement, and Fig. 4 is a cross-sectional elevation of a further modification.

The magazine A has its lower part or half tapered more or less, and may be made circular, square, oval, or have any other suitable shape.

Two diametrically opposite vertical feathers or splines, B, are formed in the magazine, and the said splines pass into diametrically-opposite notches or notched lugs C of a ring, D, fitted within the magazine, which ring has a cross-piece, D', having a downwardly-projecting hub, E, in which a screw-threaded aperture is formed, and through the said aperture

a screw-spindle, F, is passed, the upper end of which is provided with a handle, G, and is held to turn in the cross-piece H, of a ring, J, fitting in the top of the magazine, and provided on its top edge with an outwardly-projecting flange. The screw F cannot move vertically. To the ring D four, or more or less, downwardly-projecting prongs, K, are hinged, which prongs are beveled from the upper wider to the lower pointed ends, and form a tapered basket when closed. The prongs K preferably have their lower ends bent inward. If the screw-spindle F is turned in one direction, the ring D is raised, as are also the prongs K, and the lower ends of the prongs are separated by the weight of the coals, thus permitting the coals to drop. If the spindle is turned in the inverse direction, the ring D is lowered, as are also the prongs K, the lower ends of which are pressed toward each other by the bottom edge of the magazine, thus preventing the coals from dropping.

In the modification shown in Fig. 3 the prongs are hinged at their upper ends to a ring, D², secured to the magazine by screws, or otherwise, as at c c, and project through the ring D and below the bottom of the magazine. This ring D is mounted by its hub and cross-bar E D' on the lower end of the rod, and the notches C engage the splines B, just as in Fig. 1. By turning the handle G the screw will raise or lower the ring D, and thus force the lower ends of the prongs inward or allow the weight of the coal to force them outward.

In Fig. 4 the operation is the same as in Fig. 1, except the ring D and prongs K are raised and lowered by the chains L, secured thereto and to the rod m, journaled transversely in the walls of the magazine. This rod m is provided with a wheel, P, and a ratchet mechanism, n, for rotating and retaining it in any desired position.

The supply of coals delivered to the fire can be regulated very easily and rapidly, the construction of the device is very simple, the device is strong and durable, the coals and gas are fully consumed, thus preventing waste, and the device can be applied on all coal stoves, grates, &c.

Having thus described my invention, I claim as new and desire to secure by Letters Patent—

1. In a fuel-magazine for a stove or grate, a

fuel-regulator consisting of a series of hinged downwardly-projecting prongs and mechanism for contracting and expanding the opening between the lower ends of the prongs, whereby the prongs may be adjusted to regulate the descent of the coal and different sizes of coal be used therewith, substantially as described.

2. The combination, with a fuel-magazine for a stove or grate, of a vertically-movable piece to which downwardly-projecting prongs are hinged, and mechanism for opening or closing the opening formed by the lower ends of the prongs when the movable piece is operated, substantially as herein shown and described.

3. The combination, with a fuel-magazine for a stove or grate, of a vertically-movable piece to which downwardly-projecting prongs are hinged, and of a screw for raising and lowering the said piece, and mechanism for opening or closing the opening formed by the lower ends of the prongs when the movable piece is

operated, substantially as herein shown and described.

4. The combination, with a fuel-magazine for a stove or grate, of a vertically-movable piece to which downwardly-projecting prongs are hinged, feathers, slots, or splines in the magazine for guiding the vertically-movable piece, and of a screw-spindle for moving the said piece vertically, and mechanism for opening or closing the opening formed by the lower ends of the prongs when the movable piece is operated, substantially as herein shown and described.

5. The combination, with the fuel-magazine A, having its lower part tapered, of the ring J, having a cross-piece, H, the screw F in the cross-piece H, the ring D, having the hub E, and of prongs K, hinged on the ring D, substantially as herein shown and described.

ALEXANDER T. YOUNG.
